United States Patent

Des. 234,856
Patented Apr. 15, 1975

234,856

HERALDIC PLAQUE

Frank N. Allen, Libertyville, Ill. (% F. H. Noble & Company, 559 W. 59th St., Chicago, Ill. 60621)

Filed June 28, 1973, Ser. No. 374,764

Term of patent 14 years

Int. Cl. D11—02

U.S. Cl. D29—23 A

FIG. 1 is a front elevational view of a heraldic plaque showing my new design;

FIG. 2 is a right side elevational view, the left side being a mirror image thereof;

FIG. 3 is a top plan view;

FIG. 4 is a bottom plan view; and

FIG. 5 is a rear elevational view.

I claim:

The ornamental design for a heraldic plaque, substantially as shown and described.
